UNITED STATES PATENT OFFICE.

HOMER A. GENEST, OF HARTFORD, CONNECTICUT, ASSIGNOR, BY MESNE ASSIGNMENTS, TO UNITED STATES HAT MACHINERY CORPORATION, OF RICHMOND, VIRGINIA, A CORPORATION OF VIRGINIA.

FELT SHRINKING.

Application filed August 27, 1921, Serial No. 495,982. Renewed February 4, 1925.

To all whom it may concern:

Be it known that I, HOMER A. GENEST, a citizen of the United States, residing in Hartford, in the county of Hartford and 5 State of Connecticut, have invented certain new and useful Improvements in Felt Shrinking, of which the following is a specification.

This invention relates to shrinking felt 10 articles, as, for example, the bats of which fur hats are made.

According to the usual method, after a bat has been blown upon the forming cone, it is 15 dipped in scalding water and then given a preliminary manipulation, whereby it is somewhat hardened so that it can be handled with safety. Then the bat is rolled up in a blanket which is wet with hot water. The blanket and bat are then usually manipulated 20 so as to shrink the felt. It is necessary to unroll and roll up the bat in the blanket many times, and there is considerable waste of fur. Highly skilled labor is required, so that the expense of shrinking 25 the bat is excessive.

Among the objects of the present invention are to reduce the loss of fur, and to thoroughly shrink and solidify the felt and produce a superior article, and to accomplish 30 this at low cost, while expediting the work and substantially increasing the output, and permitting the employment of less skilled labor.

Other features and advantages will hereinafter appear.

In the accompanying drawings,

Figure 1 is a plan of an apparatus embodying the present improvements in one form, part of the longer of the two endless 40 belts being broken away.

Figure 2 is an elevation of the apparatus seen at Figure 1.

Figure 3 is a sectional side elevation, taken at about the line 3—3 of Figure 1; this 45 Figure 3 being diagrammatic, to illustrate the travel of the bat-shrinking belts.

Figure 4 shows a face view of a bat ready to be shrunken.

Figure 5 is an edge view thereof, showing 50 the open end.

Figure 6 shows the proportions to which the Figure 4 bat may be shrunken.

Figure 7 shows diagrammatically one belt having large knuckles and the companion belt having small knuckles, both belts weaving over and under the kneading rolls. 55

Figure 8 is a view similar to Figure 7, but showing the bat in a different position; the bat in this view having its concave side towards the small pyramids, while in Figure 7 its concave side is towards the large pyramids. 60

Figure 9 illustrates the co-operation of a belt having elastic pyramids thereon with a companion belt having no knuckles, but 65 preferably having a plain vulcanized soft rubber face, although a facing of burlap or other fibrous material may be used in some cases.

Figure 10 is a view similar to Figure 9, 70 but showing the bat bent in the opposite direction in passing around another roll.

Figure 11 is a diagram to illustrate the passage of two of the kneading belts around a roll; the pyramids on one belt being shown 75 as slightly separated, owing to the outward curvature of the belt, while the pyramids on the other belt are shown as approaching one another, owing to the inward curvature of the belt. 80

Figure 12 is a diagram to illustrate a pair of knuckled belts passing in a straight course through the machine, without applying great pressure to the bats.

Figure 13 is another diagram to show the 85 belts traveling in a straight course, while considerable pressure may be applied to the belts and the bats inserted or nested therebetween.

Figure 14 is a diagram to illustrate the 90 belts pursuing a tortuous course, as at Figure 3, while subjected to great pressure by means of supplemental pressure rolls to operate with the rolls shown at Figure 3.

After a conical bat 20, Figure 4, has been 95 blown, immersed in hot water, and given a short preliminary manipulation rolled up in a blanket, it is ready for shrinking by means of the present improvements. An edge view of the bat is seen at Figure 5, in 100 which 21 indicates the folds of the bat. At 22, Figure 6, is indicated the size to which the bat may be shrunken.

The bat 20 is laid upon a traveling bed or

pad 23 and carried along thereby to be gripped between said pad 23 and a companion traveling pad 24. Each pad is flexible, comprising a base 25, which may consist of a belt of canvas or other woven material, and a facing 26 thereon of vulcanized soft rubber preferably having a cloth insertion; soft vulcanized rubber knuckles 27 constituting protuberances which project 10 from said facing 26 and are preferably integral therewith, and preferably have the form of pyramids. These may extend in rows both longitudinally and transversely of the belt, all of the pyramids being preferably contiguous one to another widthwise as well as lengthwise of the belt. The companion belt 24 is similarly constructed, but its pyramids 28 are preferably one-half to one-third of the dimensions of the pyramids 27 on the first belt, this difference in size and spacing being preferably depended upon to avoid the tendency of the pyramids on one belt to interlock with those on the other to a serious extent. While the knuckles are 25 shown as pyramid-shaped, still projections of other forms may be employed, and such projections do not need to be regular.

The bat 20 placed upon the belt 23 may be wet by hot water delivered through a sprinkler-pipe 29, connected to a pump 30, which may draw the water from a tank 31, supplied through piping 32.

The belts 23, 24 advance together, passing around to and fro under roll 33, over roll 34, under 35, over 36, under 37, over 38, under 39 and over 40. The lower rolls occupy positions between the upper rolls, thereby causing the double belt or carrier to follow a wavy or tortuous path. By reason of its 40 following the tortuous path, the double belt or carrier is flexed alternately up and down, as indicated at Figures 7 to 10, and a corresponding flexing is effected of the inserted bat being carried along by said belts. The 45 belts are under certain longitudinal tension, and hence the bat is pressed or squeezed between them as the belts curve around the rolls, and the kneading action of the knuckles on the bat is made thorough and effective, and the shrinking of the bat expedited and its quality improved. Since the 50 pyramids are of soft rubber, they are yieldable under the pressure of the belts upon the bat, and the pyramids recover their forms 55 when the pressure is somewhat relieved, as at points midway between rolls, thereby still further kneading the bat. The pyramids on the upper belt tend to press the bat into the interstices between the pyramids of the 60 lower belt 23, thereby still further flexing or kneading the bat locally, and improving the shrinking and solidifying action.

After passing through one group of rolls 33 to 40, the belts or carriers may pass down- 65 wardly at 41, and carry the bat around a

drum 42, which is immersed in the hot water 43 in tank 31, whereby the bat is kept hot and wet, preparatory to further kneading thereof in its passage through the remaining portion of the machine.

As the double belt rises from the drum 42, it may pass over a tensioning pulley 44, which may be carried upon arms 45, pendant from a shaft or axle 46 upon which they are loosely mounted; said arms having horizontal arms 47 carrying weights 48, which tension the double belt.

The double belt may pass over a guiding drum 49 and thence down and up around alternate lower and upper rows of rolls or 80 pulleys 50, 51, 52, 53, 54, 55, 56, 57, 58, whereby the kneading, hardening and shrinking action upon the bat may be continued.

After leaving the last roll 58, the belts are 85 caused to separate, as indicated at 59, to permit the bat to be ejected; whereupon it may be again laid upon the lower belt 23 and carried through the same process, thus effecting still further hardening and shrink- 90 ing of the bat.

The upper belt 24, after leaving the pulley 58, runs down over an idle drum 60 and thence to the first roll 33, these belts being 95 endless. The long belt 23 may run back over idle drums 61, 62, 63, 64, a tensioning pulley 65, and an idle drum 66, and thence to the first pulley 33 at the intake portion of the machine. The tensioning pulley 65 may be mounted upon a pair of arms 67, pivoted at 100 68 and provided with horizontal arms 69 carrying weights 70. It is obvious that other arrangements of belts or carriers may be employed, and that the invention is not limited to endless belts, nor to belts which 105 always travel in the same direction, nor to a machine in which one endless belt loops around another endless belt from the intake to the discharge portion of the machine.

Before redepositing the partly shrunken 110 bat upon the belt 23 at the intake point, the bat may be opened out and folded in a different place, so as to avoid matting of the fibres together at the folds; or the bat may be passed through the machine several times 115 before taking or repeating such precaution.

It is obvious that several bats may be passing through the machine at the same time, being inserted therein one after another; and, inasmuch as the machine may 120 be operated successfully at a satisfactory speed, a large output may be secured. At Figure 10 the bat is shown in its first passage through the machine; and by stages it gradually shrinks and thickens as indicated 125 at Figures 9, 8 and 7, until the desired proportions and hardness are reached.

The bat will be shrunken more or less quickly according to the degree of wavy deflection which is exerted by the rolls. In 130

Figure 3 the upper rolls are shown depressed considerably into the spaces between the rolls in the second tier, making a very wavy deflection for the belt.

- 5 At Figure 11, the two belts are shown provided with pyramids of the same size and spacing; but at this figure it will be noted that as the belt is given an outward curve or bulging form in running over a pulley, 70
- 10 its pyramids tend to spread, as at the upper part of Figure 11; while when the other belt is given an inward curve at the same place, its pyramids tend to crowd together. This condition is reversed when the belts reach 75
- 15 the next pulley, and so on. Thus there is an unceasing creeping back and forth of the pyramid points of one belt relatively to those of the other belt, thus keeping up at a multitude of points all through the bat a 80
- 20 to-and-fro local manipulation and kneading thereof. This effect is secured whether the pyramids of one belt are of different size from those of the other, as at Figure 7, or the same size, as at Figure 11. The knuckle 85
- 25 action between the inner and outer belts operates to work the fur surfaces (with but little loss of fur) in such a manner as to spread and contract the fur at a multiplicity of points while digging into the fur, and 90
- 30 therefore there is a kneading action upon the fur on opposite sides and in alternate sequence. Owing to the spreading and contracting of the pyramid points, as illustrated at Figure 11, there is caused a very rapid 95
- 35 vibratory motion at a multiplicity of locations. 100

For some kinds of work, some of the advantages of elastic knuckles may be gained by utilizing only one belt having knuckles, 105

40 and providing a companion belt which is unprovided with knuckles, as at 71, Figures 9 and 10; and, in using such belts, as well as those shown at the other figures, the bat may be turned over from time to time before 110

45 being reinserted, so as to even up the action of the pyramids or knuckles upon the opposite surfaces of the bat. The felting action is illustrated in the two positions of 115

50 Figures 9 and 10, in which the bat is operated upon by the teeth or knuckles on the inner belt which co-operate with the plain belt. 120

The rolls may all be driven by a system of gearing, but preferably some of the rolls 125

55 are driven directly by the gearing and others revolve idly. A drive pulley 72^a is shown mounted upon a universal shaft 72 having spiral pinions 73, 74, 75 to mesh with spiral pinions 76, 77, 78 on the shafts of rolls 50, 130

60 54, 58, respectively; the remaining kneading rolls 52 and 56 in these groups running idly. Upon said drive shaft 72 are also spiral pinions 79 and 80, to mesh with bevel pinions 81 and 82 on the shafts of rolls 39, 35, respectively, the remaining rolls 37 and 33 of

this group revolving idly. The drive shaft 72 also has bevel pinions 83, 84 to mesh with gears 85 and 86 upon drums 49 and 60, over which runs the intermediate or short endless belt 24. A gear 87 upon the shaft of drum 78

49 meshes with a gear 88 on drum 62; and a gear 89 upon drum 60 meshes with a gear 90 on drum 61. The rolls 34, 36, 38 and 40, in the lowermost said row, all run idly, and are journaled upon a pair of horizontal bars or frames 91 common to the rolls. The rolls 51, 53, 55 and 57, in the uppermost row, also run idly, and are journaled upon a pair of horizontal bars 92 common to these rolls; 80

95 said bars 92 being adjustable upwardly and downwardly to vary the depth to which the rolls thereon sink into the spaces between the rolls 50, 52, 54, 56 and 58, thus varying the shrinking effect and securing different 85

90 results as required. Each bar 92 has at its ends slots 93, whereby it is supported upon eccentrics 94 upon shafts 95, the latter having key-stems or arbors 96, whereby they may be rotatively adjusted; said shafts 95 being journaled in their ends in brackets 97 secured upon the framework, and having tightening bolts 98 to secure the shafts where adjusted. The arrangement of the bars 91 is substantially the same as that of 92; the 95

100 bars 91 having slotted ends, and being mounted upon eccentrics 99, 100, whose mounting and equipment correspond with those of eccentrics 94. Each pair of bars 91 and 92 may be adjustably elevated or depressed at either or both ends independently of the other. Each bar may be tilted if desired by means of the eccentrics, so as to secure different desired results. 105

The framework of the machine may comprise side frames 101 suitably connected and provided with supports for the tank, pump, etc. Standards 102, rising from the corners of the framework, may support the upper and lower brackets 103, and may also contain the bearings for the drums and the two middle tiers of kneading rolls. On each side of the machine the standards 102 may be connected by integral bars 104, which have bearings for the inner rolls, viz, those 110

115 forming the second and third rows or tiers. 120

In Figure 12 the knuckled double belts are shown in a straight line, and very little pressure is exerted upon the bat, except where the belts run over the drums, and the shrinking will be very much slower. In Figure 12 there is little or no bending of the belts as they pass between the upper and lower rolls 105, 106, owing to the relatively high elevation of the upper rolls. 125

At Figure 13 the belts are shown as going straight between upper and lower sets of rolls 107, 106^a, each roll 107 being directly over or bearing upon its companion roll, whereby more pressure upon the bat may 130

be secured than at Figure 12. It will be understood that, at Figures 12, 13 and 14, the elastic rubber knuckles are employed the same as seen at certain of the other figures. At Figure 13 one set of rolls 107 may be applied to press the belts against the rolls in the other set 106^a, and thereby exert pressure upon the bat. In other words, the rolls in Figure 13 will bear directly against the knuckled belts or pads to effect shrinkage of the bat, but not such rapid shrinkage as in some of the other views. At Figure 13 the belts are shown in a straight line, the rolls bearing directly upon the belts and pressing the belts upon the underlying rolls.

At Figure 14 there are shown additional pressure rolls 108 or companion rolls, to co-operate with the rolls seen at Figure 3, 20 33 to 40 and 50 to 58. In this arrangement the rolls of each pair are offset with respect to the rolls of the next pair, giving an echelon arrangement. This provision of special pressure rolls permits applying 25 great pressure to the bat for imparting the final hardening thereto.

It will be perceived that, according to this invention, the bat may be subjected to intermittent pressure as the belts squeeze it in passing to and fro around the rolls; the pressure being relieved where the belt runs from one roll to the next. The bat is also flexed at all points, this flexing being alternately backward and forward; the 35 squeezing and flexing having substantially the effect of kneading the felt. Moreover, owing to the use of pads having elastic knuckles throughout, the knuckles on one pad tending to indent the bat at a multiplicity of points, and the knuckles on the opposite pad having a like tendency but in the opposite direction, minor manipulations are effected at a multiplicity of localities all over the bat, at the same time that the 40 bat is being given the major flections around the kneading rolls. Thus a two-fold kneading action is progressing at the same time that the bat is being intermittently pressed at the points where it curls around the rolls.

50 The knuckles, which preferably consist of closely-packed pyramids, are apt to yield somewhat to the pressure, and when the pressure is relieved they recover their forms, in doing which they effect further local manipulations of the bat; this operation occurring progressively and intermittently throughout the bat. The work is thus subjected to a variety of general and local kneading movements simultaneously as it progresses through the apparatus.

55 One of the advantages of kneading a bat between a pair of pads consisting mainly of soft rubber pyramids or knuckles, is securable by effecting slight relative to-and-fro movements of the pyramid tips on one pad

relatively to those on the other pad, this having the effect of jiggling the bat. Slight movements of the knuckle tips in each set to and fro relatively to the other set, while pressure is being applied, are highly efficient in shrinking and hardening a bat. It is by the present invention contrived to produce this relative movement, at the same time securing the other advantages hereinbefore mentioned, even though the belts travel in unison over the rolls. It is partly to accomplish this relative movement of the pyramids that the pads are caused to weave to and fro over and under the kneading rolls. It will be understood that as the pad passes around one roll and is curved outwardly thereby, the points of the pyramids separate somewhat, inasmuch as said points are more remote from the axis of the roll than are the bases of the pyramids. At the same time the companion pad, passing around the same roll but with its face toward the roll, is concaved, and the points of its pyramids are hence gathered or brought closer together. Therefore, the points or tips in one set are separated from one another, while the points in the other set approach one another, so that there is a relative traveling movement set up between the points of the two sets of pyramids as the belt goes over the roll. As the belt reverses its curve around the next roll, there is a corresponding relative traveling movement of the pyramid points, but in reverse order, the points that separated when going over the first roll being caused to approach one another as they go over the next roll, and so on for all the rolls. This slight relative traveling movement to and fro is nearly unceasing, since 105 the pyramids have their normal forms only in the straight reaches of the belts between the successive rolls. This relative creening of the points is relied upon to expedite the shrinking and hardening of the bat, 110 which is hardened not only on its exterior portions, but also on the intermediate or interior portions, thus contributing substantially to the value of the product.

It is, of course, obvious that my invention 115 is susceptible of various modifications and changes which would be within the spirit of the invention without departing from the scope of the following claims.

Having thus described my invention, I 120 claim:

1. A bat-shrinking apparatus comprising two sets of cooperating rolls, the axes of the latter being so located that the rolls of one set are in overlapping relation to the 125 rolls of the other set, and traveling pads guided alternately over and under successive rolls and caused thereby to follow a wavy path, each of said pads comprising numerous elastic knuckles to knead a bat 130

- carried in a substantially flat condition between the pads, the aggregate of said knuckles occupying practically the entire working area of each pad.
- 5 2. A bat-shrinking apparatus comprising two successive groups each comprising two sets of rolls, the rolls in one set of each group being in staggered and overlapping relation to the rolls of the other set of each 10 group, a pair of traveling endless bat-kneading belts bending alternately over and under the successive rolls in each group for kneading bats in a substantially flat condition, and a hot water bath through which the 15 belts run between said groups, the working face of each belt provided with numerous elastic kneading knuckles, the aggregate of which occupy practically the entire working area of each belt.
- 20 3. A bat-shrinking apparatus comprising two successive groups each comprising two sets of rolls, the rolls in one set of each group being in staggered and overlapping relation to the other set of each group, a 25 pair of traveling endless bat-kneading belts bending alternately over and under the successive rolls in each group for kneading bats in a substantially flat condition, one of said belts being relatively short, drums over 30 which the short belt reverses its direction of travel, said groups of rolls being disposed between said drums; the long belt comprising two loops, one of said loops for each 35 group of kneading rolls; and guiding drums upon which the long belt runs back from
- the delivery to the intake point of the apparatus.
4. The combination of a travelling pad having numerous individual knuckles for kneading a bat in a substantially flat condition, the aggregate of said knuckles comprising practically the entire area of the pad, a succession of rolls located in staggered, overlapping relation around which the pad bends to and fro, thereby alternately spreading and gathering the tips of the knuckles and a companion travelling pad for confining the flat bat against said knuckles.
- 40 5. The combination with a pair of travelling belts between which a bat in a substantially flat condition may be carried, each of said belts having numerous soft rubber points the aggregate of which comprises practically the entire working area of each 50 belt, of means for effecting to-and-fro creeping of the points upon each belt relatively to those upon the other belt, and means for causing the points to press into the bat.
- 45 6. The method of shrinking a bat, comprising placing the bat in a substantially flat condition between pads provided with elastic knuckles the aggregate of which comprises practically the entire working area 55 of said pads, and repeatedly bending all portions of the assemblage to and fro.
- 60 HOMER A. GENEST.
